UNITED STATES PATENT OFFICE.

CHARLES H. RIDDERSTEDT, OF PITTSBURGH, PENNSYLVANIA.

COMBUSTION OF FUEL.

1,328,296.

Specification of Letters Patent. Patented Jan. 20, 1920.

Application filed November 19, 1918. Serial No. 263,115.

To all whom it may concern:

Be it known that I, CHARLES H. RIDDERSTEDT, a citizen of the United States, residing at Pittsburgh, in the county of Allegheny and State of Pennsylvania, have invented certain new and useful Improvements in the Combustion of Fuel, of which the following is a specification.

The principal objects of the present invention are, first, to effect an economy in the combustion of fuel; second, to obtain the advantages of burning pulverized fuel but without the disadvantage of pulverizing it; third, to avoid clinkers and air holes and to 15 keep a level fire of any thickness; fourth, to effect substantially complete combustion; and fifth, to afford perfect control of the rate of combustion.

To these and other ends hereinafter set forth the invention, stated in general terms, comprises the improvement in the combustion of fuel which consists in keeping it in a state of suspension or semi-suspension while being burned.

The invention will be claimed at the end hereof, but will be first described in connection with the embodiment selected from other embodiments for the sake of illustration in the accompanying drawings forming 30 part hereof and in which—

Figure 1, is an elevational view partly in section.

Fig. 2, is a plan view, drawn to an enlarged scale of the jigger with parts broken 35 away, and

Figs. 3 and 4, are sectional views on the lines 3—3 and 4—4 of Fig. 2.

The invention is shown in connection with the combustion of fuel, as coal, in the combustion chamber of a boiler for generating steam, and the invention will be described in that connection, but without intending to limit the application of the invention to that use. 1, is an element or contrivance which 40 is designated a jigger, because it both has and causes when in use rapid jerky motion, and this element 1, is also a grate in the sense that air passes through it in order to support combustion, but unlike most grates 45 the ashes do not pass through it, but are discharged over its end. The jigger 1, is shown as inclined in order to facilitate the travel of fuel in respect to its surface. The jiggling

mechanism for the jigger 1, is susceptible of embodiment in many forms, since the object 55 is to keep the fuel or the particles of the burning fuel bed in a state of suspension or semi-suspension through the rapid and continuous jumping, dancing or bounding motion imparted by the vibration of the jigger. 60 As shown the jigger 1, is vibrated horizontally in lateral direction and rapidly oscillated vertically about its discharge end as a center. However, it may be jiggled or vibrated in other directions appropriate for 65 keeping the fuel or fuel-bed in a state of suspension or semi-suspension. The jigger element 1, is shown as mounted on a wheeled carriage 2, capable of vibration as by means of a crank 3, and crank-arm 4, of which the 70 fulcrum is adjustable by means of the adjusting screw 5, to vary the amplitude of the vibrations. One end of the jigger element 1, is shown as pivoted to the carriage at 6, by means of a shoe 7, and adjustable 75 eccentric 8, so that the jigger element can be adjusted from horizontal to any inclination desired in order to control the rate of travel of the fuel. The other end of the jigger element 1, is acted upon by the star-wheel 9, 80 driven by the connection 10, and is guided by the guide 10^a. The star-wheel 9, is shown as acting upon an anvil member 11, adjustably connected with the jigger by a screw 85 thread and jam nuts 12, so that this anvil member can be adjusted to modify and control the action of the star wheel and to increase and diminish the amplitude of the oscillations of the jigger member. 13, is a feed control for the fuel, which need not be 90 powdered, but which is preferably of small size, and 14, is an apron for confining the ash and products of combustion. The way shown for supplying air to support combustion of the suspended or semi-suspended fuel 95 includes draft-box provisions 15, for the jigger element 1. Air is led to the draft box 15, by a suitable flexible connection or connections 16, valved, and from the draft box by apertures 17, which may be large enough 100 for its passage, yet small enough in connection with the pressure of the air blast for excluding fuel and products of combustion. 20, indicates means for adjusting the valve of the connection 16. The draft box may be 105 subdivided into compartments, as shown in

Fig. 3, each supplied by a different air connection, so that different portions of the suspended or semi-suspended fuel-bed may be supplied with an appropriate draft or supply of air.

The mode of operation may be described as follows: The jigger mechanism vibrates the jigger element 1, which keeps the fuel-bed in a state of suspension or semi-suspension, and in a state of combustion supported by the air supplied above the jigger element 1. Fuel is fed in at 13, and the ash escapes at 18. The rate of combustion is under the control of the operator who can regulate not only the quantity of fuel supplied, but also the rate of travel by means of the feed mechanism 13, and the means 8, for adjusting the inclination of the jigger element 1. Furthermore the motion which causes the suspension or semi-suspension of the fuel can be increased or diminished by the described adjustments of the jiggling mechanism. Inasmuch as the fuel-bed is in a state of suspension or semi-suspension it follows that fused ash may not agglomerate into the form of clinker, nor can air holes form, so that a clean and level fire is maintained at all times of any desired thickness and the conditions are appropriate for perfect combustion. 19, are screens removably mounted on the element 1, and they can be removed and cleaned if necessary and then replaced.

The fuel is in a bouncing state, because it is caused to leap or drop against the jigger and rebound by reason of the rapidly accelerated or quick jerky motions imparted to the jigger. It might be said the solid fuel is bounced because the fuel bed is raised by the jigger which is suddenly dropped, so that the solid fuel falls to the face of the jigger by gravity and then rebounds from the rising jigger, and repetitions of this action keep the solid matter in a state of suspension or semi-suspension above the jigger through which it does not pass. When the jerky motions of the jigger are lateral and vertical the ash off-take may be open and unobstructed. The star wheel is an example of a cam, tappet or hammer-blow or impact mechanism which bounces the fuel into and keeps it in a state of suspension or semi-suspension, so violent that there is powdering or tendency to powdering of the fuel.

It will be obvious to those skilled in the art that modifications may be made in details of construction and arrangement and in mere matters of form. Hence my invention is not limited as to such things or otherwise than as the appended claims and the prior state of the art may require.

I claim:

1. Improvements in the combustion of fuel comprising the combination of a jigger impervious to the passage of solid ingredi-

ents of the fuel bed, means for supplying air through the jigger for supporting combustion, and cam jigger mechanism for rapidly jiggling the jigger to bounce the solid ingredients of the fuel bed, substantially as described.

2. Improvements in the combustion of fuel comprising the combination of a jigger impervious to the passage of solid ingredients of the fuel bed, means for supplying air through the jigger for supporting combustion, vertically and transversely acting jigger mechanism for rapidly jiggling the jigger, provisions for feeding fuel at one end of the jigger, and an off-take for ash at the other end of the jigger, substantially as described.

3. Improvements in the combustion of fuel comprising the combination of an inclined jigger impervious to the passage of solid ingredients of the fuel bed and in respect to which the fuel feeds, means for supplying air through the jigger for supporting combustion, and vibratory impact mechanism for continuously jiggling the jigger to keep the fuel in a bouncing state, substantially as described.

4. Improvements in the combustion of fuel comprising the combination of an inclined jigger impervious to the passage of solid ingredients of the fuel bed and in respect to which the fuel feeds, means for supplying air through the jigger for supporting combustion, vibratory impact mechanism for continuously jiggling the jigger to keep the fuel in a bouncing state and means for adjusting the inclination of the jigger when in operation to control the travel of the fuel.

5. Improvements in the combustion of fuel comprising the combination of a jigger impervious to the passage of solid ingredients of the fuel bed and in respect to which the fuel feeds, means for supplying air through the jigger for supporting combustion, impact mechanism for jiggling the jigger to keep the fuel in a bouncing state, and devices for changing the throw of the jiggling mechanism, substantially as described.

6. Improvements in the combustion of fuel comprising the combination of a combustion chamber, a movable carriage arranged in the chamber, a jigger pivotally connected at one end to the carriage, a jiggling cam device carried by the carriage and adapted to operate vertically upon the other end of the jigger, means for transversely vibrating the carriage and air connections to the top of the jigger, substantially as described.

7. Improvements in the combustion of fuel comprising the combination of a combustion chamber, a jigger arranged in the combustion chamber perforated for the pas-

sage of air and not for the passage of fuel and ash, means for supplying air through the jigger, and jiggling hammer-blown mechanism for the jigger, substantially as described.

8. In combination a combustion chamber, a fuel supporting element therein impervious

to the passage of solid fuel ingredients, means for imparting quick jerky motions to the element to toss the particles of fuel and 10 keep the fuel bed in a bouncing state, and means for supplying air, substantially as described.

CHARLES H. RIDDERSTEDT.
